UNITED STATES PATENT OFFICE

2,627,964

SAFETY DEVICE FOR RECORD FEEDING
CONTROLS

Harold R. Wood, Endicott, N. Y., assignor to International Business Machines Corporation, New York, N. Y., a corporation of New York

Application March 17, 1951, Serial No. 216,230

3 Claims. (Cl. 197—127)

1

This invention relates in general to record feeding devices and more particularly to safety devices provided for power driven record feeding rollers.

The main object of the invention is to provide means for insuring that fingers and objects are not caught between the frame work of a printing machine and power driven paper feed rollers.

A further object of the invention is the provision of a safety bar or idler roller in the bight between a platen cylinder and a paper feed table on a power driven machine.

Another object of the invention is the provision of electrical interlocks for safety devices to insure that the safety device is on and properly seated in the printing machine. As illustrated in the present case the insulation end of an inserted safety bar acts to close contacts in series with the feed clutch magnet and driving motor for the power driven platen or paper feed rollers, thus insuring that if the safety bar is not in place the rollers cannot be driven to catch objects or fingers in the narrow space between power driven members and the frame of the machine.

Other objects of the invention will be pointed out in the following description and claims and illustrated in the accompanying drawings, which disclose, by way of example, the principle of the invention and the best mode, which has been contemplated, of applying that principle.

In the drawings:

Fig. 1 is a perspective view of the platen and safety bar with the drive gearing and the control circuits therefore.

Fig. 2 is an enlarged detail in partial section showing the insulated plunger in the safety bar.

As may be seen in Fig. 1, the platen P is driven to feed a record sheet S by means of a train of gearing and a motor M. On the motor shaft is a driving worm 21 in mesh with a worm gear wheel 22 attached to a drive gear 23. The latter is in mesh with a gear 24 attached to one side 25 of a normally open clutch C the other side of which is fastened to an operating gear 26.

The clutch C is controlled by a magnet LS which is called into operation under control of tabulator cards and a feed control tape as set forth in the Patent No. 2,531,885 to A. W. Mills et al., filed on August 9, 1945, issued November 28, 1950, and in the patent application Serial No. 29,535 filed on May 27, 1948, by F. J. Furman, now Patent No. 2,558,947, issued July 3, 1951.

When the clutch C is connected, the gear 26 drives an idler gear 27 which is in mesh with a pinion 28 fastened to the platen shaft 29. A

2

record sheet S is guided down into the bight between the pressure rollers PR and the platen P by a paper table T which may be considered as part of the carriage frame. As the platen P is rotated clockwise, the sheet is advanced into position relative to the printing line along the front of the platen.

If the platen P is unprotected, there is a dangerous area in the bight between the paper table T and the platen P wherein fingers and objects are subject to being forcibly drawn down into the narrow paper path. Since the platen P is rather strongly turned, there is need to prevent crushing of finger tips and prevent distortion of carriage parts by the wedging of a dropped object such as a pencil in the exposed bight.

Therefore, a safety bar SB is provided as an elongated round cover for the bight area. The bar SB does not interfere with the insertion of record sheets S but it is close enough to table T and platen P to prevent anything but a very flat material from being drawn around the platen P.

Bar SB is loosely and removably mounted between the side frames of the carriage and extends across the entire width of the platen P. At the left end, bar SB is fitted into a hole or depression in the left side frame 46. At the right end the bar is fitted with an extending insulation plunger the tip of which fits into a hole in a contact box B fastened to the right side frame. Inside the box B is a pair of normally open contacts 45 the blades of which are spaced and fastened to the box by insulation spacers so that the left blade is near the inner wall and next to the opening for the tip of the safety bar SB so that when the bar is assembled, the blade is shoved over to the right by the tip and the contacts 45 are closed. Before describing the clutch and motor control circuits involving contacts 45 it is believed well to note the interior construction of the safety bar SB as shown in Fig. 2.

There it is noted that the left end of bar SB is shaped with a reduced end 35 for fitting into the opening in frame 46. The right end of the bar is hollowed at 37 to receive the sliding insulation plunger 38 which is shaped with a collar 39 and an extending tip 36 which is shaped to fit into the hole in box B and to extend therein far enough to operate contacts 45. A reduced section 40 of the bar permits the inward projection of a set screw 43 which cooperates with the shoulders of the plunger to act as a limiting stop for its sliding motion.

Against the widened end 41 of the plunger 38 there is pressed one end of a compression spring

42 assembled in the bottom of opening 37 and tending to keep the plunger 38 extended to hold the bar SB assembled between the carriage frames.

The control circuits for the clutch magnet LS and motor M are so arranged that the platen P can be driven only when the safety bar SB is in place. This is done by putting contacts 45 (which are closed only when the bar is in the protective position) in series with the circuits for the magnet LS and motor M. It is understood that either control is effective alone as well as in combination as shown.

Power is applied between the lines L1 and L2 by the closure of the switch PS to the power supply through wire 50. A circuit through feed clutch magnet LS includes line L1, wires 56, 57, contacts 45 (closed only by presence of safety bar SB), wires 47 and 54, clutch magnet LS, wire 55, contacts OC (representative of other controls as disclosed by the patent and application referred to hereinbefore), wire 50 and line L2. Then the clutch C is closed and the platen P is driven to feed the record sheet.

Of course, in order for the clutch to be effective to drive, the motor M must also be operated. The controls for the motor M could be invariable and independent of contacts 45 instead of dependent thereon as shown. However, it is evident that in the case of a continuous train of gearing, or in an instance involving a fixed closed clutch, it is desirable to have the motor M under safety control as well as the clutch.

The circuit for the motor M includes line L1, wires 56, 57, contacts 45, wires 47 and 53, motor switch MS, wire 52, motor M, wire 51 and line L2.

Therefore either or both the motor drive and clutch control are normally ineffective, but conditioned for operation by insertion of the safety bar SB and consequent closure of contacts 45.

A pair of normally open safety switches SS1 and SS2 are provided to induce clutch and motor operation independently of the safety contacts 45. This is a provision for use when other blocking attachments, such as bill feed devices, etc., block the platen bight and remove the need for the safety bar. Another instance of the use of switches SS1 and SS2 is when they are provided only for serviceman use and otherwise hidden from ordinary operation.

Closure of switch SS1 provides a circuit for clutch magnet LS through line L1, wire 56, switch SS1, wire 54, magnet LS, wire 55, contacts OC and wire 50 to line L2.

Closure of switch SS2 operates motor M by a circuit through line L1, wires 56 and 58, switches SS2 and MS, wire 52, motor M and wire 51 to line L2.

While there have been shown and described and pointed out the fundamental novel features of the invention as applied to a preferred embodiment, it will be understood that various omissions and substitutions and changes in the

form and details of the device illustrated and in its operation may be made by those skilled in the art, without departing from the spirit of the invention. It is the intention, therefore, to be limited only as indicated by the scope of the following claims.

What is claimed is:

1. In a paper feeding device, a frame therefor, a platen roller mounted in said frame, a main operating means, a clutch between said main operating means and said roller, a removable safety bar mounted in said frame to block objects from being caught between the roller and the frame, a magnet for controlling said clutch, and a circuit for said magnet including a pair of normally open contacts, said contacts being closed by said safety bar when it is mounted in the blocking position.
2. In a record feeding device, a frame therefor, a platen roller rotatably mounted in said frame, a main operating means for rotating said roller, a clutch between said main operating means and said roller, a removable safety bar mounted in said frame to block objects from being caught between the roller and the frame, a magnet for controlling said clutch, and circuits for said main operating means and said clutch magnet including a common pair of normally open contacts, said contacts being closed by said safety bar when it is mounted in the blocking position.
3. In a sheet feeding device, a platen roller rotatably mounted in said device, a set of pressure rollers cooperating with the platen, a paper table mounted at a tangent to said platen roller to guide the sheets thereon, a drive motor, a train of gearing including a clutch between the motor and the platen roller, a magnet for controlling the clutch, an electric circuit for the magnet including a pair of normally open contacts, a pair of side frames for the device, one of said frames being formed with a socket and the other carrying a box, said box containing said contacts and formed with an opening adjacent a contact, and a removable safety rod formed with one reduced end to fit into said socket and containing a spring pressed insulation plunger at the other end, said plunger being formed with a reduced end to protrude into said box opening and close said contacts, said rod when mounted occupying the bight between the platen roller and paper table and keeping objects from being caught therein.
